UNITED STATES PATENT OFFICE.

SAMUEL M. VAUCLAIN, OF PHILADELPHIA, PENNSYLVANIA, ASSIGNOR TO BURNHAM, WILLIAMS & COMPANY, OF PHILADELPHIA, PENNSYLVANIA, A FIRM.

BOILER FOR LOCOMOTIVES.

No. 927,299.

Specification of Letters Patent.

Patented July 6, 1909.

Application filed January 21, 1909. Serial No. 473,402.

To all whom it may concern:

Be it known that I, SAMUEL M. VAUCLAIN, a citizen of the United States, residing in Philadelphia, Pennsylvania, have invented 5 certain Improvements in Boilers for Locomotives, of which the following is a specification.

My invention relates to that type of a locomotive known as an articulated locomotive; *i. e.*, one in which two frames each carrying independent sets of driving mechanism are coupled together by a pivot, so that while the locomotive has a long wheel base it will readily take the curves of the track. 10 In this type of locomotive the boiler is firmly attached to one frame and overhangs the other frame; it being carried on the frame which it overhangs by suitable supports. The boilers of these locomotives have been 20 made as a single boiler so that in the event of one frame being detached from the other the overhanging portion of the boiler had to be jacked up or otherwise supported.

One object of my invention is to make the 25 boiler in two sections; one section being carried by one frame and the other section being carried by the other frame; the two sections of the boiler being bolted together when the locomotive is in use so that in operation it will be, in fact, one boiler, the overhanging portion adapted to move over the frame by which it is carried. By this construction I can uncouple the two sections of the boiler and detach one frame from the 35 other so as to move the frame apart and also separate the boiler sections so that access may be had to the interior of the boiler to remove the tubes or to otherwise repair the interior parts of the boiler.

40 A further object of this invention is to provide the boiler with two sets of comparatively short tubes instead of the long single set now in use.

In the accompanying drawing:—Figure 1, 45 is a side view of an articulated locomotive, showing my improved construction of boiler; Fig. 2, is a view similar to Fig. 1, showing the parts of the boiler separated; Fig. 3, is an enlarged, sectional, perspective view 50 through the joint of the boiler; Fig. 4, is a view similar to Fig. 3, showing the parts

separated; Fig. 5, is an edge view of one of the parts; and Fig. 6, is a view of a modification.

A is the rear frame of an articulated locomotive. B is the forward frame; the two frames being pivoted together by pivot pins *c* in the manner common to this type of locomotive. The frame A is mounted on the driving wheels *b* and cylinders A' are situated at the forward end of the frame. The usual intervening mechanism is provided for driving said wheels. The frame B is mounted on driving wheels *b* and carries the low pressure cylinder B' and is also provided with intervening mechanism for driving the wheels. 55 60 65

D is the boiler made in two sections D' and D''. This boiler is rigidly mounted on the frame A and overhangs the forward 70 frame B. The overhanging portion of the boiler is supported on suitable standards C carried by the frame B; the boiler in the present instance having saddles C', which rest upon these supports. By this construction the frames are free to take the curves of the track; the boiler being rigidly mounted on the rear frame, its forward end will move laterally over the frame B. 75

The ordinary practice is to make the 80 boiler as a single structure; the tubes being of considerable length and difficult to replace when necessary. Attempts have been made to make secondary combustion chambers in the boiler and to run comparatively 85 short tubes from the fire box to the combustion chamber and from the combustion chamber to the smoke box, but these tubes are also difficult to remove, owing to the cramped space of the secondary combustion 90 chamber, which, if made of any size, materially decreases the tube space of the boiler.

By my invention I make the boiler in two independent sections, and in the present instance provide each section with a flange, 95 and when the two frames A and B are coupled together the two flanges are brought in contact and bolts or other fastenings may be provided for firmly securing the flanges together so as to make the boiler, in fact, 100 a single structure and I provide the section D' with a tube sheet *d'* and extend tubes *e*

from the fire box D^3 to the said tube sheet d' , and I provide the section D^2 with a tube sheet d^2 and extend the tube e' to the tube sheet of the smoke box D^4 . The two tube sheets d' and d^2 may be arranged any distance from the flanged ends of the boiler sections D' , D^2 , as desired, according to the space necessary, and the tubes e , e' , may be of different diameters, if desired.

10. If the space D^5 between the tube sheets d' and d^2 , which is, in fact, a secondary combustion chamber, is adapted to receive a superheater or feed water heater, then the two tube sheets d' , d^2 are set back to such an extent as to leave space to receive the superheating or other structure. But, if the space is not to be occupied by any other structure, then the tube sheets d' , d^2 may be placed close together, if desired.

20. While the joint between the two sections may be made in any manner desired, I prefer to use the joint illustrated in Figs. 3 and 4, in which d is the flange on the section D' and d^3 is the flange on the section D^2 . One flange has a beveled projection adapted to a beveled recess in the other flange and bolts i extend through both flanges and couple them together, the V-shaped abutting faces making comparatively tight joints and properly alining the two sections of the boiler.

30. The flanges may be secured to the sections by rivets, as shown, or by any other fastenings, if desired.

In Fig. 6, I have shown a flange on each 35 section consisting of an angle plate with transverse bolts passing through the projecting flanges of the plates.

By the above description it will be seen that the boiler has two independent steam 40 spaces. These steam spaces may be connected as shown or may be made entirely independent; one steam space being connected to one set of cylinders and the other steam space being connected to the other set of 45 cylinders.

If the engine is to be used as a compound engine, then steam may enter first the cylinders on one frame and be carried to the cylinders on the other frame by suitable flexible 50 connections, as shown, or may pass, after leaving one set of cylinders, to the tubes of a superheater before entering the second set of cylinders, and this superheater may be located in the space D^5 or in the smoke box D^4 , 55 as desired, depending upon the type of engine to which my invention is applied.

I claim:

1. The combination in an articulated locomotive, of two frames pivoted together, a 60 boiler mounted rigidly on one frame and overhanging the other frame, said boiler being made in two sections, one section detachably connected to the other.

2. The combination in an articulated loco-

motive, of two frames pivoted together, a 65 boiler mounted rigidly on one frame and overhanging the other frame, said boiler being made in two sections, the overhanging section being detachably secured to the fixed section, and means for supporting the overhanging section upon that frame over which it extends.

3. The combination in an articulated locomotive, of two frames pivoted together, a 70 boiler rigidly mounted on one frame and overhanging the other frame, said boiler being made in two sections, each detachably secured together, means for supporting the overhanging detachable section of the boiler when the two sections of the boiler are detached, said means acting to properly support the overhanging section when connected to the rigid section and to allow it to move laterally in respect to the frame over which it extends.

4. The combination in an articulated locomotive, of two frames pivoted together, a 75 boiler rigidly mounted on one frame and extending over the other frame, said boiler being made in two independent sections, means 80 for securing the sections together, each section having independent tubes and tube sheets.

5. The combination in an articulated locomotive, of two frames pivoted together, a 85 boiler rigidly mounted on one frame and extending over the other frame, supports carrying the overhanging portion, said overhanging portion being made separable from the fixed portion of the boiler, tube sheets 90 at the abutting ends of each section forming a space or secondary combustion chamber, and tubes attached to the tube sheets.

6. The combination in an articulated locomotive, of two frames pivoted together, a 105 boiler rigidly mounted on one frame and extending over the other frame, said boiler being made in two sections, means for coupling the two sections together, and tube sheets at 110 the abutting ends of the said sections, said tube sheets being mounted within each section some distance from the abutting ends so as to provide a secondary combustion chamber or a space for the location of a superheater or other apparatus.

7. The combination in an articulated locomotive, of two frames pivoted together, a 120 boiler mounted rigidly on one frame and overhanging the other frame, said boiler being made in two sections, a flange on each section, means for securing the two sections together so as to rigidly connect the two sections, independent tubes in each section, and means for supporting the overhanging portion of the boiler on the frame over which 125 it extends.

8. The combination in a boiler having a fire box at one end, a smoke box at the other

end, and an intermediate combustion chamber, tubes connecting the combustion chamber with the fire box and the smoke box, said boiler being made in two sections, the 5 parting being at the combustion chamber, and means coupling the two sections rigidly together.

In testimony whereof, I have signed my name to this specification, in the presence of two subscribing witnesses.

SAMUEL M. VAUCLAIN.
